UNITED STATES PATENT OFFICE.

HENRY J. MEYERS, OF LOS ANGELES, CALIFORNIA.

FOLDING BED.

1,352,909.

Specification of Letters Patent. Patented Sept. 14, 1920.

Application filed June 6, 1917. Serial No. 173,154.

To all whom it may concern:

Be it known that I, HENRY J. MEYERS, a citizen of the United States, residing at Los Angeles, in the county of Los Angeles and State of California, have invented a new and useful Folding Bed, of which the following is a specification.

This invention relates to a folding bed and particularly pertains to a bed of the 10 vertically swinging type.

In folding beds of the type adapted to be swung in and out of closet openings, it is usually necessary to construct the bed of a length shorter than that of the ordinary 15 bed to avoid forming the closet opening of disproportionate and unsightly height or forming the closet space with a sunken floor in order to give the space required to swing the bed vertically on its support and 20 to provide room for counterbalancing elements.

It is the object of this invention to provide a folding bed of compact construction and so arranged as to permit a spring frame 25 and mattress of a length of six feet and four inches being swung vertically and passed through an opening six feet and eight inches in height.

Another object is to provide a vertically 30 movable folding bed having a foot board pivotally and slidably mounted thereon in such manner that it may be lowered on the bed frame when the latter is at or near its vertical position to dispose the upper edge 35 of the foot board substantially on a plane with the upper end of the bed frame and in which the foot board is detachably connected to the frame so that various styles and designs of foot boards may be constructed to be interchangeably connected to the bed frame.

Another object is to provide a horizontally 40 shifting pivotal mounting for the bed frame whereby the head end portion of the bed frame projecting beyond the pivotal mounting thereof may be caused to move on a vertical plane, in swinging the bed frame up or down.

A further object is to provide a spring 50 counterbalance so constructed and arranged that it may be readily attached to bed heads of various styles now generally in use and which will permit the bed with its counterbalance being moved about in either its 55 open or closed position.

Other objects will appear hereinafter.

The invention is illustrated in the accompanying drawings, in which:

Figure 1 is a perspective view illustrating the bed in its open position. 60

Fig. 2 is a view in side elevation, showing the bed in its open position in full lines and indicating the closed position in dotted lines.

Fig. 3 is a detail in perspective of the 65 pivotal mounting of the bed whereby the latter may be swung in and out of a closet opening.

Fig. 4 is a detail section and elevation showing the shifting pivotal mounting of 70 the bed frame and the arrangement of the counterbalancing springs.

Fig. 5 is a detail section on the line 5—5 of Fig. 4.

Fig. 6 is a detail section and elevation 75 illustrating the slideable and pivotal mounting of the foot board.

Fig. 7 is a section on the line 7—7 of Fig. 6.

More specifically 9 indicates the head rail 80 of the bed which embodies side posts 10 fitted with casters 11.

In carrying out my invention a rectangular frame, comprising horizontally extending end bars 12 and side rods 13 and 85 14, is rigidly attached to the lower ends of the posts 10 and is provided with casters 15 spaced in front of the casters 11 and forming a base on which the bed superstructure is carried. Standards 16 extend 90 upwardly above the casters 15 and carry horizontally extending guide bars 17 on their upper ends. The guide bars are provided with pivot pins 18 which extend into sockets on the upper ends of the standards, 95 forming pivots on which the guide bars may swing laterally. Mounted on the guide bars to slide lengthwise thereof are sleeves 19 which form bearings for horizontally extending trunnions 20 carried by the side 100 rails 21 of the bed frame. The side rails are upturned on their inner ends and pivotally connect with a horizontal bar 22 having guide ways on its ends which slidably engage vertical dovetail guide flanges 23 105 carried by the posts 10. Connecting with the bar 22 is a series of springs 24 which pass under direction rollers 25 carried by the rod 13, and are connected to an angle iron bar 26 carried on the rear of the head 110

rail. These springs serve as a counter-balance in swinging the side rails and the bed vertically.

The outer ends of the side rails 21 are rigidly connected to the ends of an angle iron 27 which may constitute the end member of a bed spring, the other end member of which comprises an angle iron 28 carried at the bend of the inner ends of the side rail. A woven wire mattress support 29 is suspended between the angle irons 27 and 28 and connect therethrough by coil springs 30.

Pivoted at 31 on the angle iron 27 adjacent each end thereof are depending guide ways 32 adapted to slidably receive slide ribs 33 formed on the side posts 34 of the foot rail 35. The guide ways 32 are open at their upper end to receive the guide ribs and are provided with stops 36 at their lower ends to engage the guide ribs and limit the downward movement of the latter within the guide ways. The foot rail is thus detachably connected to the guide ways so as to be interchangeable. The upper ends of the guide ways are offset in relation to their pivots 31 and are formed with shoulders 37 which extend beneath the angle iron 27 as shown in Fig. 6. These shoulders are so arranged in relation to the guide ribs that when the bed is in its horizontal position and the foot rail is supported on the floor, the shoulder will be disposed intermediate the guide ribs so that the upper ends of the guide ribs will extend into locking stirrups 38 carried on the angle iron 27; these stirrups being formed with channels open at their lower ends to receive the upper ends of the guide ribs and closed at their ends by flanges 39 against which the upper ends of the guide ribs are adapted to abut. As a means for locking the foot rail against movement in relation to the guide ways when the bed is in its horizontal position and the guide ribs are disposed to engage both the locking stirrups and the upper ends of the guide ways a spring pressed latch 40 is mounted in one of the posts 34 to engage the flange 39.

As a means for swinging the bed frame in and out of a closet when in its folded position the frame is pivotally connected to an arm 41 at the center of the head rail 9, the arm 41 being pivoted at 42 to the floor at a point within the closet. The connection between the bed and the arm 41 comprises a yoke 43 carried by the bed frame the lower leg of which is formed with a fork 44 adapted to be disposed astride of a pin 45 carried on the arm 41 and the upper end 60 of which is adapted to be detachably connected to the arm 41 by a removable pivot pin 46 as shown in Fig. 3. By removing the pin 46 the bed frame may be detached from the arm 41 and moved about on its casters either in its open or closed position.

For the purpose of automatically swinging the foot rail to fold and unfold same in raising and lowering the bed, a drag link 47 is pivotally connected to the bar 14 and branches at its outer end into pivotal engagement with the lower end of the guide ways 32.

Assume the bed to be in its horizontal position as shown in Fig. 1 and as indicated in full lines in Fig. 2 in which position it will be locked against upward movement by the latch 40 as shown in Fig. 6 with the springs 24 under tension. The foot rail will be rigidly held in a vertical position by reason of the guide ribs being engaged in the vertically alined channels of the guide ways and locking stirrups. When the parts are thus positioned the bed may be freely moved about on its casters on disengaging the pivot pin 46. When it is desired to raise the bed into its folded position the latch 40 is disengaged from the flange 39 whereupon the lower end of the bed frame is lifted in relation to the foot rail, as indicated in dotted lines in Fig. 6, to dispose the guide ribs entirely within the guide ways, which are then free to rock on their pivots 31. On moving the foot portion of the bed upwardly the drag link will swing the guide ways inwardly so that they will extend substantially with the side rails when the latter are disposed in their vertical position as indicated in dotted lines in Fig. 2. The foot rail will then be lowered in relation to the guide ways and supported by the guide ribs seating on the stops 36 and will thus be disposed with the top of the foot rail extending on a plane with the foot portion of the bed frame.

In swinging the bed frame upwardly it turns on the trunnions 20 and the bar 22 moves downwardly on the guide flanges 23. As the inner end of the bed moves downwardly the sleeves 19 advance on the guide bars 17 to shift the trunnions or pivotal point of the bed frame so that the bar 22 may travel vertically on the guide flanges 23, the sleeve moving back to a normal position on the guide bar as the bar 22 traverses the lower half of its path of travel. When the bed frame has reached its vertical position the weight thereof will be disposed rearward of its pivotal mounting so that the upturned end of the bed frame will seat on the bars 12.

In lowering the bed frame the sleeves 19 and the bar 22 will pass through movements reverse to that just described, the guide ways 32 with the foot rail thereon being disposed vertically by the action of the drag link 47. On depressing the forward portion of the bed the locking stirrups will be moved astride of the guide ribs whereupon the latch 40 will reengage the locking stirrups to lock the bed against vertical movement on its pivot thus effectively holding the bed frame against being moved to its folded

position in event a load is imposed on the bed frame rearward of its pivotal mounting.

Throughout the vertical movement of the bed frame the springs 24 will operate to 5 counterbalance the frame.

From the foregoing it will be seen that I have provided a folding bed which is simple and compact in construction and which, by reason of the head end of the bed frame being positioned near the floor and the foot rail disposed substantially flush with the upper end of the bed frame when the bed is in its vertical position, will permit constructing the bed proper of a length but a 10 few inches shorter than the height of the opening through which it is to pass.

While I have shown and described a specific construction it is manifest that various changes may be made without departing from the spirit and scope of the invention as set forth in the appended claims.

I claim:

1. In a folding bed, a pivoted bed frame, 25 guide ways pivotally connected thereto, a foot rail slidably connected to said guide ways, and means for locking said foot rail against movement in relation to the guide ways.

2. In a folding bed, a pivoted bed frame, 30 guide ways pivotally connected thereto, a foot rail, guide ribs on said foot rail slid- able in said guide ways, and locking stirrups engageable with said guide ribs to hold the guide ways and guide ribs in interlocked en- 35 gagement.

3. In a folding bed, a pivoted bed frame, 40 guide ways pivotally connected thereto, a foot rail, guide ribs on said foot rail slidable in said guide ways, locking stirrups engageable with said guide ribs to hold the guide ways and guide ribs in interlocked engage- 45 ment and a latch on said foot rail engageable with said locking stirrup.

4. In a folding bed, a head member em-

bodying side posts, vertical guide flanges on 45 said posts, a pair of standards arranged forward of the posts and connected thereto, horizontal guide bars pivoted on said standards, sleeves slidable on said guide bars, a bed frame having side rails pivoted to said 50 sleeves, said side rails having upturned head ends, and a horizontal bar connecting the extremities of the head end slidably attached to the vertical guide flanges.

5. In a folding bed, a head member em- 55 bodying side posts, vertical guide flanges on said posts, a pair of standards arranged forward of the posts and connected thereto, horizontal guide bars on said standards, sleeves slidable on said guide bars, a bed 60 frame having side rails pivoted to said sleeves, said side rails having upturned head ends, a horizontal bar connecting the extremities of the head end slidably attached to the vertical guide flanges, a rod connect- 65 ing the lower ends of the posts, a series of direction rollers on said rod, a bar carried by the posts above the rod, and counter- balancing springs connecting the bar on the 70 posts and the bar on the bed rails and pass- ing around the direction rollers.

6. In a folding bed, head frame posts, 75 vertical guide flanges thereon, a vertically movable bar slidably engaged with the guide flanges, a bed frame to the head end of which said bar is pivotally connected, a pair of 75 guide bars pivoted to swing horizontally and sleeves slidable thereon to which the bed frame is pivoted.

7. In a folding bed, a bed frame, a pair 80 of members to which said bed frame is pivoted adjacent to its head end to swing vertically, said members being mounted for reciprocal movement and to swing on a vertical axis, and a vertically reciprocal 85 guide member pivoted to the head of the bed frame.

HENRY J. MEYERS.
